UNITED STATES PATENT OFFICE.

HENRY H. CUTLER, OF BROOKLINE, MASSACHUSETTS.

INTERNAL-COMBUSTION ENGINE.

Application filed February 28, 1924. Serial No. 695,864.

My invention relates to internal combustion engines and more especially to such engines of the variable clearance type in which means are provided for varying the clearance space in unison with the movement of the power piston for securing more complete scavenging of the cylinder after every explosion.

The present invention is a development of that disclosed in my application Serial No. 445,690, filed February 17, 1921, of which this application is a continuation.

Variable clearance engines of the type shown in my Letters Patent 1,301,658 issued April 22, 1919, on an application filed May 18, 1917, are subject to certain limitations due chiefly to the demonstrated impossibility of preventing leakage around the piston rings of the supplemental piston.

The principal object of the invention is to provide a supplemental piston so constructed and arranged as to form with the cylinder head an airtight chamber, of such volume that the air compressed therein by said supplemental piston will attain a pressure equal approximately to that exerted on the combustion chamber face of said supplemental piston during the power and compression strokes and thereby form a pneumatic cushion limiting the outward movement of said supplemental piston. This object I attain by the use of a ringless supplemental piston so constructed and arranged that the contacting portions of the cylinder and supplemental piston are maintained at substantially the same temperature thereby permitting of a substantially gastight fit of said supplemental piston in said cylinder without the frictional loss due to the use of piston rings.

One embodiment of my invention whereby the foregoing object is obtained consists of a hollow supplemental piston having its cylindrical wall arranged within and closely fitting into the space between the interior wall of the cylinder and the reduced end portion of a hollow plug extending into the cylinder and closing end thereof, said hollow plug communicating with the water-cooling system so that the cylindrical wall of the supplemental piston is cooled on the inside by the water inside of said plug, and on the outside by the water in the jacket of the cylinder.

Other objects of my invention and novel features of construction are hereinafter set

forth, and the constructions whereby said objects are realized are particularly pointed out in the appended claims.

My invention is the result of experimental work and experience derived largely from constructing and operating the internal combustion engine described in my Letters Patent No. 1,301,658, dated May 18, 1917, as well as other engines similar to the types illustrated herewith.

The main object of my present invention is the same as that set forth in the above mentioned patent, namely, to provide means for automatically effecting complete mechanical scavenging of the cylinder at the end of every exhaust stroke, and to avoid the undesirable features which the testing of this earlier type of engine developed.

These undesirable features were, first, excessive leakage by the scavenging pistons of both oil and the working mixture, plainly visible in this type of engine, and giving an ocular demonstration of the large amount of leakage that takes place by the power pistons of all internal combustion engines, no matter how well constructed. Second, there was also developed a large additional loss due to friction of the piston rings of the scavenging pistons, inertia losses in stopping and accelerating the comparatively heavy scavenging pistons, connecting rods, etc., and the still further friction losses of all the other extra moving parts. Third, the net result was only a slight increase in economy and available power.

My present invention aims to overcome all of the above mentioned undesirable features, as well as to simplify and cheapen the mechanical construction.

The accompanying drawings show two slightly different embodiments of my invention.

Figure 1 is a longitudinal vertical section of a four cylinder internal combustion engine embodying my invention, and showing the relative position of the moving parts on completion of the compression stroke in cylinder numbered 10 in said figure.

Fig. 2 is a longitudinal vertical section taken through the middle of one of the engine cylinders at right angles to Fig. 1 showing the relative position of the moving parts at the beginning of the power stroke.

Fig. 3 is a section similar to Fig. 2 illustrating a modification of my invention, and showing the relative position of the mov-

ing parts at the end of the exhaust stroke.

In place of the usual demountable head, I provide a single unit head consisting of the casting 17 secured by bolts 17' (Fig. 1), to 5 the top of the cylinder block 14 in the usual manner. In the casting 17 cylinders 18, 19, 10 20 and 21 are formed and constitute extensions of preferably smaller diameter than the cylinders 10, 11, 12 and 13, respectively, 15 of the main engine block 14. It will be understood that such cylinder extensions may be formed in any other suitable manner such as casting them integral with the engine cylinders.

15 At the extreme end of each cylinder extension is a fixed head or plug 22, 23, 24 and 25, respectively, each head being hollow and connected with the water jacket by passageways 26, 26. It is essential that there shall be 20 a gas and water-tight joint between the fixed head and the wall of the cylinder in which it is placed. While such gas-tight joints may be effected in various ways, I prefer to shrink the cylinder on to the head by 25 turning the latter a few thousandths of an inch larger in diameter, at the top, than the bore of the cylinder, then heating the entire cylinder casting and placing the heads therein in cold, so that when the cylinder casting 30 cools, the heads will be firmly gripped. This has been found in practice to be sufficient not only to make a perfect water and gas-tight joint, but also to stand the pressure of the exploded gases under working 35 conditions.

Arranged for longitudinal movement in each cylinder is a movable member 28, 29, 30 and 31, respectively, the portion or volume of each cylinder between the power pistons 40 32, 33, 34 and 35 and said movable members 28, 29, 30 and 31, respectively, forming compression chambers 75, and means are provided for automatically controlling the position of said movable members 28, 29, 45 30 and 31 to vary the volume of said compression chamber 75 in accordance with the variation of the load on the engine. The position of said movable members 28, 29, 30 and 31 is controlled automatically and 50 silently for the purposes above specified, and after each explosion of the working mixture the position of said movable members 28, 29, 30 and 31 is changed automatically in order to effect the complete mechanical 55 scavenging of the cylinders, such control of position being effected by combined spring and pneumatic means.

In Fig. 1 dash-pot pistons 36, 37, 38 and 60 39 are shown arranged to work in a cylinder formed in the fixed cylinder heads 22, 23, 24 and 25, and rods 40, 41, 42 and 43 passing through the said fixed heads 22, 23, 24 and 25 to serve to connect each dash-pot piston with its 65 respective scavenging piston. It is essential that the said piston rods 40, 41, 42 and 43

should make a practically gas-tight joint where they pass through the fixed heads 22, 23, 24, and 25, and at the same time have no tendency to cramp the scavenging pistons in case said piston rods were not fastened absolutely in the center of the said scavenging piston. I provide for this contingency by attaching the piston rods to their respective scavenging pistons in such a way as to allow of a very slight lateral movement 75 at the joint between the two, but without allowing any vertical play.

This feature is accomplished by means of the heads 40', 41', 42' and 43' formed on the end of each piston rod, which heads are 80 inserted in a hole turned in the scavenging piston and then covered with washers 40^a, 41^b, 42^c, 43^d riveted as shown to the scavenging pistons so as to allow of no vertical lost motion, but a slight amount of lateral lost 85 motion or play. The ends of said piston rods 40', 41', 42' and 43' are preferably threaded and screwed into the dash-pot pistons 36, 37, 38 and 39 and then fastened with taper pins or set screws.

Attached rigidly to each one of the dash-pot pistons 36, 37, 38 and 39 are strong spiral springs 45^a, 45^b, 45^c, and 45^d, respectively, the other end of said springs being fastened in like manner to collars 46^a, 46^b, 46^c and 46^d. The preferred methods of attaching said springs to said dash-pot pistons and collars is by means of electric arc welding. It is evident that a spring constructed in this manner may be used either as a compression or a tension spring. All the collars are threaded inside and held to a channel iron cross bar 52 by means of bolts 53^a, 53^b, 53^c and 53^d. 95

The scavenging piston 28 is shown lifted 105 by the compression in cylinder number 10, Fig. 1, thereby compressing the spring 45, and in Fig. 2 the scavenging piston 28' has compressed the spring 45' still further, due to the increased pressure of the explosion of 110 the working mixture at the beginning of the power stroke.

The scavenging pistons 28, 29, 30 and 31 are shown in the drawings with extremely thin walls and no piston rings. These walls 115 slide freely between the walls of the cylinders 18, 19, 20 and 21, and the fixed heads 22, 23, 24 and 25. And since both the outside of said cylinders and the inside of said fixed heads are kept filled with the water supplied by the water cooling system of the engine, the said scavenging pistons 28, 29, 30 and 31 are subjected both inside and outside 120 to the cooling effect of the water. This means that the top part of the walls of said scavenging pistons will be kept at approximately the same temperature as that of said cylinders and fixed heads, and can consequently be made such a close fit that leakage becomes too small to require piston rings. 125 130

This construction results in a form of piston which will allow a minimum amount of leakage as well as a minimum amount of friction and resulting mechanical wear, and 6 constitutes an important feature of my invention, since many of the well known troubles experienced with the power pistons of all internal combustion engines are done away with.

10 In the position shown in Fig. 1 the power piston 32 is at the end of its compression stroke just before ignition takes place. The power piston 33 is at the end of its intake stroke, piston 34 at the end of its power 15 stroke, and piston 35 at the end of its exhaust stroke.

When the power piston 32 was moving inwardly (upwardly) during its compression stroke, and before reaching the position 20 shown in Fig. 1, it was gradually compressing the working mixture in the compression chamber 75, and the pressure in said chamber 75 was gradually moving the scavenging piston 28 upward against the combined pressure of the powerful spring 45 and the air compressed in the chamber 76 between the inner face of the scavenging piston 28 and the fixed head 22.

The distance which the scavenging piston 30 ton is moved inwardly during the compression stroke varies with the amount of working mixture which has been admitted to the cylinder during the intake stroke, determined by the amount of opening of the 35 throttle valve on the carburetor. It will thus be seen that the position of the scavenging piston with respect to the power piston is automatically controlled resiliently and will vary the volume of the compression 40 chamber in accordance with the variation of the load on the engine.

It should not be understood however that this action maintains the degree of compression approximately constant under variable 45 load, as it is manifest that the more the springs 45 are compressed, as well as the air in the chambers 76, the greater must be the pressure in the chambers 75. In order to maintain a fairly constant compression under variable load, it is manifest that a constant pressure upon the scavenging pistons 50 would have to be maintained at any and all positions to which these were moved.

The construction shown in the accompanying 55 drawings does not permit therefore of maintaining a constant degree of compression under a variable load, and such a requirement necessitates a very different form of construction.

60 The working mixture having been compressed in the chamber 75, it is then fired by means of the spark plug 66 and the scavenging piston 28 is forced up nearer to the fixed head 22, as shown in Fig. 2. Inasmuch as

mixture may result in a pressure of three or four hundred pounds per square inch, it will be obvious that no spring could be made to withstand this relatively great pressure and still be sufficiently elastic to return the scavenging piston 28 in time to keep step with an engine running at one or two thousand revolutions a minute. All springs possess a very appreciable time lag, the larger and more powerful the spring, the slower it can 75 vibrate. I therefore design my spring 45 so as to have sufficient strength to resist the pressure of the compression of the working mixture and depend upon the pneumatic cushion of air in the chamber 76 to absorb 80 or resist the pressure of the working mixture at the time of the explosion and thus prevent the scavenging piston from striking the fixed head 22.

To effect this result it is essential that 85 said chamber 76 be absolutely airtight, and that the juxtaposed faces of the head and piston shall be exactly the same shape, so that there will be no projection on the one not matched by an indentation on the other. 90 The air in the scavenging piston chamber 76 can then be raised to an enormous pressure and the scavenging piston can never be forced against the head which obviously 95 would be fatal to operation.

The air in the chamber 76 cannot leak by the scavenging piston 28 into the compression chamber 75, because the pressure of the burning gases in the chamber 75 is initially much greater than the pressure of air in the chamber 76, inasmuch as the pressure in the compression or combustion chamber 75 acts to partly compress the spring 45, as well as to partly compress the air in the chamber 76. Therefore any leakage past the scavenging piston 28 would be from the combustion chamber 75 and would simply supply additional air or gas to assist in cushioning the scavenging piston 28 and thus prevent its striking the fixed head 22.

That there is no perceptible leakage from the chamber 76 by the piston rod 40 into the dash-pot chamber has been fully demonstrated in practice.

Now as soon as the charge has been fired, 115 the power piston 32 moves outwardly on its power stroke, and the pressure of the burning gases between the power piston and the scavenging piston 28 falls off. This will allow the pressure back of the scavenging piston to move the same downwardly and inwardly so as to maintain the total pressure approximately equal on both sides of the scavenging piston. This process goes on until the exhaust valve starts to open, 120 which generally occurs when the power piston has completed about seven-eighths of its power stroke. Now since the pressure of the burning gases, at the time of the exhaust valve starts to open, is almost invari- 130

ably considerably less than the corresponding pressure of compression, it is evident that the scavenging piston 28 will have moved down (inwardly) to a position considerably lower than it occupied at the end of the compression stroke, which latter position is shown in Fig. 1. Thus the energy stored up in the compression of the spring 45 and the compressed air in the chamber 76 will have been restored to the engine in the shape of useful work.

The exhaust valve now opens slowly, but allows the pressure of the gases in the engine cylinder to fall off quite rapidly, the pressure of the spring 45, together with that of the air in the chamber 76, is now free to push the scavenging piston down so as to quite quickly reach its normal position as indicated by the scavenging pistons 29, 30 and 31. These pistons, together with their rods, dash-pot pistons, etc., will thus acquire more or less momentum causing them to move down somewhat lower than their normal position. This action however will stretch the springs 45, as well as compress the air under the dash-pot pistons 46 so that the scavenging pistons will be promptly brought back to normal position in a smooth and noiseless manner.

Since the springs 45 are made very strong, the pressure of a pound or two back pressure of the exhaust gases will not be sufficient to cause any appreciable upward movement of the scavenging pistons, so that at the end of the exhaust stroke the power piston will approach very close to the scavenging piston and thus mechanically expel all of the spent exhaust gases except the small amount contained in the valve chamber 79 (Fig. 2), which in the drawings submitted amounts to but 6½% of the total contents of the engine cylinder at the end of the intake stroke. The percentage of adulteration in the standard non-scavenging engine of this particular make figures about 28%.

It is obvious that a compressed mixture of hydro-carbon gas, adulterated with 6½% of dead inert gases will burn with far greater efficiency and resulting pressure than one adulterated with 28% of dead gas, which gain in efficiency and available power is the chief advantage of my invention.

It is furthermore obvious that, as previously pointed out, unless the air chamber 76 is so constructed that the compressed air within it cannot escape, the device becomes inoperative, and that in order to obtain such an air-tight chamber, it is essential to employ a carefully fitted piston rod of comparatively small diameter and considerable length, and that any attempt to hold back the compressed air by means of a piston and rings exposed over its entire diameter to the outside atmosphere cannot possibly result in

obtaining an air-tight chamber that would prevent the scavenging piston from striking the fixed head in practice.

Fig. 3 illustrates an embodiment of my invention in its simplest form, in which the spring 45' is not employed to control the amount or degree of compression in the engine, but said spring is made relatively very much weaker than the spring 45 (Fig. 2) so as to exert a pressure upon the plunger 28' of not over two pounds per square inch, or just enough to hold the dash-pot piston 36' to its seat against the back pressure of the exhaust during the latter part of the exhaust stroke.

In order to distinguish the spring 45' from the spring 45, the spring 45' is shown drawn in single lines and not in section.

The chamber 76', Fig. 3, is shown somewhat smaller in volume than chamber 76. Fig. 1, otherwise the compression stroke of the engine could not compress the working mixture to the same amount as there is practically little to resist the upward movement of the plunger 28' except the compression of the air in the chamber 76'.

At the end of the compression stroke the plunger 28' will have moved up until the pressure on both sides of the scavenging piston 28' is practically the same, and then when the explosion occurs will move up a very little closer to the fixed head 22' than was the case with scavenging piston 22, Fig. 2.

The construction shown in Fig. 3 possesses the marked advantage over that shown in Fig. 2 in that the scavenging piston 28' becomes almost practically incapable of leaking in practice to any appreciable amount for the reason that the pressure of the air inside the scavenging piston 28' at all times almost exactly balances the pressure of the working mixture outside the said piston, and at times this balance of pressure is identical as can be mathematically demonstrated as follows. As a practical demonstration of this truth we will apply my invention to the engine most universally used in this country, of which there are more in use than all other makes combined.

The drawings submitted show the following dimensions:—Diameter of scavenging pistons $3\frac{1}{2}'' = 9.62$ sq. in. area, diameter of piston rods $\frac{1}{6}'' = .15$ sq. in. area, strength of spring 45' at 2 lbs. per square inch = 9.62 $\times 2 = 19.24$ pounds, strength of spring 45' when compressed $\frac{1}{2}$ inch = 19.24 pounds, height of chamber 76' = $1\frac{1}{3}''$.

Now assume that at the time of exploding the working mixture a gauge pressure is realized of 300 pounds per square inch. The scavenging piston 28' will then be forced up to within about $\frac{1}{16}''$ of the fixed head 22', thereby compressing the spring 1 $\frac{1}{16}$

inches more; therefore total compression of spring $= \frac{1}{2} + 1\frac{1}{16} = 1\frac{3}{8}$ '. Spring 45' will then exert a total pressure on the scavenging piston 28' of $\frac{19.24}{8} \times 25 = 60.125$ pounds.

Let x equal pressure of air inside the scavenging piston 28' then $x(9.62 - .15) + 48.1 = 9.62 \times 300$. $9.47x = 2886 - 48.1 = 2825.875$ pounds, therefore $x = 298.4$ pounds, a difference in pressure of but 1.6 pounds between the two sides of the scavenging piston.

Using the same data and assuming that an explosive pressure was realized of 400 pounds to the square inch, the resulting pressure (x) inside the scavenging piston would be about 399.98 pounds. If only 200 pounds was obtained (x) would equal about 197 pounds and at 60 pounds compression (x) equals about 55.7 pounds.

When it is considered that the power pistons of the engine have to withstand the entire pressure of the explosion with no opposing pressure in the crank case, that power pistons cannot be made to fit closely in the cylinders, that the friction of the piston rings and thrust of the connecting rods soon wears the cylinders out of round, it must be admitted that as compared with the power pistons, my scavenging piston 28' is from a practical and commercial standpoint absolutely leakless, and that consequently none of the working mixture is lost by leaking by the scavenging piston during the compression stroke, and also that the friction and wear of my scavenging piston is negligible.

Since the air in the chamber 76' will quickly become hot and thereby tend to increase in pressure, I have provided the small air vent hole 77' which connects with the outside air by means of the hole 78' drilled from the upper end of the piston rod 40' to meet said hole 77'. This construction prevents any accumulation of air or gas in the chamber 76'.

The chief advantage of the construction shown in Figs. 1 and 2 over that shown in Fig. 3 consists in the greater amount of resilient recoil possible at the time of the explosion. This extra movement of the scavenging piston by quickly enlarging the volume of the combustion chamber at the instant the working mixture is fired, serves to absorb the wave of high pressure which occurs at this time. This property of the working mixture now in common use is an important determining factor in limiting the amount of compression an engine can stand without knocking, and forces designers to use a lower compression at the expense of both economy of fuel and greater available power.

Having thus described two illustrative embodiments of my invention without however

limiting the same thereto, what I claim and desire to secure by Letters Patent is:—

1. In an internal combustion engine the combination with a cylinder and power piston of a supplemental piston located between said power piston and the head of said cylinder, said sub-piston being constructed and arranged to form with said head an air-tight chamber of such volume that the air compressed therein by said supplemental piston during the power and compression strokes will constitute a pneumatic cushion limiting the outward movement of said supplemental piston, and a spring rigidly attached at one end to said sub-piston and also rigidly attached at the other end to a stationary part of the engine for resisting the movement in either direction of said sub-piston and automatically returning the same to its normal position.

2. In an internal combustion engine the combination with a cylinder and power piston of a supplemental piston located between said power piston and the fixed head of said cylinder, said supplemental piston being constructed and arranged to form with said head an air-tight chamber of such volume that the air compressed therein by said supplemental piston during the power and compression strokes will constitute a pneumatic cushion limiting the outward movement of said supplemental piston, and a combined compression and tension spring rigidly attached at one end to said supplemental piston and also rigidly attached at the other end to a stationary part of said engine, said spring being thereby adapted to resist the movement in either direction of said supplemental piston and thus capable of returning the same to its normal position, after being moved from said normal position in either direction by the action of said engine.

3. In an internal combustion engine the combination with a cylinder and its power piston of a supplemental piston located between said power piston and the head of said cylinder and forming with said head an air-tight air chamber, a piston rod connected with said sub-piston and reciprocable in a relatively long bearing in the said head, and a combined compression and tension spring rigidly attached to said piston rod at one end and to a rigid support at the other end for holding said sub-piston in a normal fixed position and resisting the movement of the same in either direction.

4. In an internal combustion engine the combination with a cylinder and power piston, of a supplemental piston located between said power piston and the head of said cylinder, said supplemental piston being so shaped as to fit closely over a projection of the head of said cylinder so as to form an air-tight chamber wherein a pneumatic cushion for said supplemental piston is

- formed during the outward movement of said supplemental piston to prevent the latter from striking said cylinder head during the power and compression strokes, and a combined compression and tension spring attached at either end to said supplemental piston and said cylinder head, respectively, so as to resist the movement of said supplemental piston in either direction, and automatically and silently return the same to its normal position during the intake and exhaust strokes of the engine.
5. In an internal combustion engine the combination with a cylinder and power piston therein, of a supplemental piston subject to the pressure of the working mixture of said cylinder, said supplemental piston being located between said power piston and the head of said cylinder and constructed and arranged to form with said head an airtight chamber wherein a pneumatic cushion is formed by the outward movement of said supplemental piston to prevent the latter from striking against said head during the power and compression strokes, and a spring attached at its two ends to said supplemental piston and said
- head respectively and having sufficient strength only to hold said supplemental piston in normal position, when not subjected to the pressure of the working mixture in said cylinder during the compression or working strokes of the engine.
6. In an internal combustion engine the combination with a cylinder and power piston of a supplemental piston located between said power piston and the head of said cylinder, said supplemental piston being constructed and arranged to form with said head an airtight chamber, and a spring having its ends attached, respectively, to said supplemental piston and a stationary part of the engine, said supplemental piston and spring being so constructed, proportioned and arranged that at all points in the cycle the gaseous pressure exerted on the outward surface of said supplemental piston is substantially equal to the pressure exerted by the working mixture on the inward surface thereof.
- 10 15 20 25 30 35 40 45 50
- In testimony whereof, I have hereunto subscribed my name this 26th day of February, 1924.

HENRY H. CUTLER.
